UNITED STATES PATENT OFFICE.

JAMES CLARKE HAGEY, OF CHICAGO, ILLINOIS, ASSIGNOR TO THE CABLE COMPANY, OF CHICAGO, ILLINOIS, A CORPORATION OF ILLINOIS.

EXPRESSION DEVICE FOR MUSICAL INSTRUMENTS.

Application filed August 12, 1921. Serial No. 491,689.

To all whom it may concern:

Be it known that I, JAMES CLARKE HAGEY, a citizen of the United States, residing at Chicago, in the county of Cook and State of Illinois, have invented new and useful Improvements in Expression Devices for Musical Instruments, of which the following is a full, clear, concise, and exact description, reference being had to the accompanying drawing, forming a part of this specification.

My invention relates to expression devices for musical instruments.

In order that the invention may be readily understood, it is here stated that it has heretofore been usual to provide for the obtaining of soft or "piano" effects in grand pianos by arranging for a short lateral movement of the piano action from its normal position. For ordinary playing, the action is allowed to remain in normal position and a hammer, when actuated, will strike and cause the vibration of three strings. For obtaining a softer effect, the action may be moved laterally, with respect to the strings, so that a hammer, when actuated, will strike and cause the vibration of only two strings. This provision for the obtaining of softer tone effects is not, however, suitable for use with the usual player-grand-piano, as the shifting of the piano action also involves the shifting of the piano keys, and this would interfere with the player-mechanism, or vice versa. The usual player-grand-piano comprises a plurality of key-actuating stickers, one for each key, which project through the piano key-bed and engage under the rear ends of the keys to lift the same and cause the hammers to strike the strings. It is clear that any attempt to shift the piano keys laterally, while any of the key-actuating stickers were in raised position, would result in jamming the raised sticker or stickers against the adjacent unraised key or keys, and the force with which this lateral adjustment of the piano keys is usually made would probably cause serious damage to the stickers or to the keys, or to both. It has, therefore, been the practice to provide for the obtaining of soft or "piano" effects in player-grand-pianos through some adjustment other than one which involves lateral movement of the keys.

One of such other adjustments consists in

lifting the hammers closer to the strings to effect a shortening of the hammer stroke and a consequent decrease in the force of the hammer blow upon the strings. To accomplish this lifting of the hammers, a movable hammer-rest-rail is provided, extending beneath the stems or shanks of the hammers. For ordinary playing, the hammers are allowed to rest in normal or lowered position and a hammer, when actuated, will travel its full stroke in delivering its blow upon the strings. For obtaining a softer effect, the hammer-rest-rail may be raised to lift the hammers nearer the strings and a hammer, when actuated, will travel a shorter distance in delivering its blow upon the strings. This provision for the obtaining of softer tone effects is not, however, suitable for use during the manual playing of the keys, as the lifting of the hammers involves the lowering of the front ends of the keys, making shallow what is known as the "dip" and seriously interfering with what is known as the key "touch." This objectionable result is due to the fact that, in grand pianos, the keys are carefully and accurately "balanced" to properly counteract the weight of the hammers upon the rear ends thereof, and the lifting of the hammers, by means of the movable hammer-rest-rail, takes the weight of the hammers from the rear ends of the keys, the forward ends of which consequently drop as the rear ends rise to follow the lifting of the hammers and the intermediate elements of the hammer or piano action.

The hereinbefore described usual method of providing for the obtaining of soft or "piano" effects by arranging for a short lateral movement of the piano action involves a similarly short lateral movement of the piano keys, but such an adjustment does not disturb the proper dip of the keys nor interfere with the key touch.

It is therefore apparent that, in providing for the obtaining of soft or "piano" effects in player-grand-pianos, the lateral adjustment of the piano action and piano keys is more desirable when the instrument is being played manually, and is not at all desirable or advisable when the instrument is being played by means of the player-mechanism. It is likewise apparent that the lifting adjustment of the hammers for this purpose, by means of the movable hammer-rest-rail,

is more desirable when the instrument is being played by means of the player-mechanism, and is not at all desirable, but exceedingly objectionable, when the instrument is being played manually. My invention is designed to permit the proper one of these adjustments to be made, when desired, under the respective proper circumstances or conditions, and to prevent the 10 improper one of said adjustments to be made at such times.

In the drawings, in which several embodiments of my invention are shown,--

Figure 1 is a view, in front elevation, 15 of part of a player-grand-piano, parts thereof being broken away and parts of the player-mechanism being omitted;

Fig. 2 is a horizontal sectional view, on the line 2—2 of Fig. 3, showing a part of 20 the piano action;

Fig. 3 is a vertical sectional view of the front part of the instrument, on the line 25 3—3 of Fig. 1;

Fig. 4 is a vertical sectional view, showing another form of my invention;

Fig. 5 is a fragmentary vertical sectional view, showing another form of my invention;

Fig. 6 is a sectional view, on the line 30 6—6 of Fig. 5; and

Fig. 7 is a fragmentary vertical sectional view, showing still another form of my invention.

The player-grand-piano construction 35 shown in the drawings comprises the key-bed 10, the piano action 11, the pivoted fall-board 12, the string-plate 13, the strings 14, the wrest-plank 15, the pedal-lyre 16, the 40 pedals 17, 18, and 19, the player-mechanism action 20 for actuating the piano action, the hammer-rest-rail 21, the pneumatic 22 for actuating the hammer-rest-rail, and means 23 for automatically rendering the "piano" 45 pedal 17 ineffective when the instrument is being played by means of the player-mechanism.

With the exception of the means 23 for automatically rendering the "piano" pedal 17 ineffective, the construction of the parts 50 above referred to may be substantially the same as has heretofore been employed in grand pianos or in player-grand-pianos. The hammer-rest-rail 21 may be made in two, or even more than two, sections and a 55 pneumatic, such as I have shown at 22, may be employed for actuating each of said sections. Such a construction of the hammer-rest-rail does not, however, form a part of my invention and will not be further described herein, since the function and 60 operation of the individual sections, and of the several respective pneumatics for actuating said sections, would be the same as that of the single hammer-rest-rail 21 and the single 65 pneumatic 22 which I have shown.

It appears advisable, however, to emphasize one fact which I have already described, namely, that in many, if not all, player-grand-piano constructions, when the instrument is being played by means of the 70 player-mechanism and the pneumatic 22 is actuated to lift the hammer-rest-rail 21 to shorten the stroke of the hammers 24, the front ends of the keys 25 will drop down a distance corresponding to the distance which 75 the hammers and the intermediate parts of the hammer or piano action are lifted. As before stated, this lowering of the front ends 80 of the keys so interferes with the proper key touch as to be very objectionable to a pianist and it is, therefore, desirable to provide the instrument with a device which will permit a pianist to obtain soft or "piano" effects without the described usual dropping of the front ends of the keys. For the reasons 85 hereinbefore mentioned, it is, nevertheless, desirable to employ some means for permitting soft or "piano" effects to be obtained which will not result in, or permit, the lateral shifting of the keys during the playing 90 of the instrument by means of the player-mechanism. It appears to be advisable, therefore, to employ both of the described 95 adjustments of the piano hammers, the vertical or lifting adjustment to be used during the use of the player-mechanism and the lateral adjustment to be used during manual playing, and to prevent the use of each of such adjustments under reverse conditions 100 or circumstances. For this purpose, I arrange the connection of the "piano" pedal 17 so that, when the instrument is being played manually, a depression of that pedal by the pianist will effect the described lateral 105 adjustment of the hammers, and so that, when the instrument is being played by means of the player-mechanism, a depression of the "piano" pedal will be ineffective.

As will hereinafter appear from the description of my invention, it would be easy 110 to provide for the actuation of the hammer-rest-rail 21 by means of the "piano" pedal 17, during the playing of the instrument by means of the player-mechanism, instead of rendering the actuation of that pedal entirely ineffective under such circumstances, but I believe that such an arrangement 115 would be inadvisable, since, as I have before mentioned, the hammer-rest-rail is often constructed in separately movable sections, 120 and the actuation of these sections is separately accomplished through the actuation of individual pneumatics. The actuation of these individual pneumatics is usually controlled automatically from the music or note 125 sheet, and any interference with such automatic control is rarely, if ever, desirable. In addition to this reason for my not providing such an arrangement, it would appear to be 130 inadvisable to provide separate pedals for

the individual actuation of the plurality of hammer-rest-rail sections, and I know of no sufficient reason for further complicating the closely arranged construction of a grand piano action by providing for the actuation of the entire length of the hammer-rest-rail, or the simultaneous actuation of the plurality of sections thereof, by the "piano" pedal. Such an actuation is possible, although not especially provided for, in many player-upright-pianos but is seldom, if ever, employed during the use of the player-mechanism, and such use is generally acknowledged to be detrimental, rather than beneficial, to the proper rendition of a musical selection. Other means are usually provided for reducing, when desired, the power of the full-stroke blow of the hammers, such as, for instance, a means for controlling the power with which the player-mechanism is actuated.

The mechanism for transmitting motion of the "piano" pedal 17 to the laterally movable piano action 11 comprises a push-rod 26 and a bell-crank-lever 27. The lower end of the push-rod rests upon the rear end of the pivoted pedal 17 and the upper end of the push-rod is normally positioned beneath the end part of the longer horizontally extending arm of the bell-crank-lever 27. The bell-crank-lever is pivotally mounted at 28 in or upon the key-bed 10 and, in addition to the longer horizontally extending arm, has a shorter upright arm which projects through the key-bed and engages against the side of a recess or groove 29 in the under side of the laterally movable key-frame 30. The key-frame 30 carries the entire piano action 11, including the hammers 24 and the hammer-rest-rail 21, as well as the keys 25, and is slidably supported upon the key-bed 10 in any suitable manner. At the right side of the key-frame, a bow-spring 32 is provided, the middle part of which is secured to the adjacent casing-arm and the ends of which bear against the side of the movable key-frame to yieldably hold it in normal position. Depression of the forward end of the pedal 17 rocks the pedal upon its pivot, raises the rear end thereof and the push-rod 26, rocks the bell-crank-lever 27 upon its pivot 28, and moves the key-frame 30 to the right, compressing the bow-spring 32 and positioning the piano action so that a hammer, when actuated, will strike only two of the three strings, for the respective note. Release of the pedal 17 will permit the parts to return to their normal positions, the piano action being returned under the influence of the bow-spring 32, so that a hammer, when actuated, will strike the three strings pertaining to the respective note. It will be understood, of course, that proper stops (which I have not shown) may be placed to insure correct positioning

of the laterally movable piano action at each end of the described lateral movement thereof.

The action 20 of the player-mechanism comprises a plurality of striker-pneumatics 33 and a plurality of key-actuating stickers 34, one each for each of the piano keys 25. The lower end of each sticker 34 is connected with one of the pneumatics 33, and the upper end of each sticker projects through the key-bed 10 and is located directly beneath the rear end of one of the piano keys 25. The collapse of any one of the pneumatics 33 will consequently raise its respective sticker 34, lift the rear end of the piano key located over that sticker, and thus actuate the corresponding hammer 24.

As it would not be feasible, for the reasons already given, to move the piano action laterally to permit soft or "piano" effects to be obtained, while the instrument was being played by means of the player-mechanism, I provide for the obtaining of these effects, during such playing of the instrument, through the use of the hammer-rest-rail 21 and the pneumatic 22. The hammer-rest-rail (or the sections thereof, if a sectional rail is employed) extends along beneath the stems or shanks of the hammers 24 and is provided with a plurality of swinging arms 35 (Figs. 2 and 3) which are pivotally secured to the piano action-rail 36 to swing about substantially the same axis as do the hammers 24. The hammer-rest-rail is actuated by the pneumatic 22 through the lift-rod 37, the lower end of which is secured to the movable leaf of the pneumatic 22 and the upper end of which engages with the under side of the hammer-rest-rail 21. The upper end part of the lift-rod 37 passes through and is guided by the guide-rail 38, and the lower part thereof passes freely through openings in the key-bed 10 and key-frame 30, which openings are large enough to permit the short lateral movement of the piano action to be made during manual playing without damage to the lift-rod 37 or the parts associated therewith. The pneumatic 22 is arranged to be automatically controlled in operation from perforations suitably placed in the music or note sheet.

From the description thus far, it will be seen that two mechanically operable expression devices are provided for obtaining soft or "piano" effects, one to be controlled by the pianist through actuation of the "piano" pedal 17, during manual playing of the instrument, and the other to be automatically controlled in operation from the music sheet. It has also been pointed out that the first of these two devices, which involves a lateral movement of the piano keys, cannot be used, while the instrument is being played by means of the player-

mechanism, without danger of injury to the construction. In order, therefore, to insure against such possible injury, I provide the mechanism 23, which will prevent the 5 lateral movement of the piano action by means of the pedal 17 during the operation of the player-mechanism. This mechanism 23 is arranged to automatically render the pedal 17 ineffective while the player- 10 mechanism is in operation.

The mechanism 23 comprises a pneumatic 39 and a link 40, one end of the link being connected to the movable leaf of the pneumatic and the other end thereof being pivotally connected at 41 to the push-rod 26. The pneumatic 39 is connected, by a conduit 42, with the wind-chest 43 of the player-mechanism action 20, or, if preferred, with some other chamber or conduit of the play- 15 er-mechanism more directly associated and connected with the air-rarefying apparatus.

In order to play the instrument by means of the player-mechanism, it is necessary that the air in the wind-chest 43 shall be rarefied. 20 Rarefaction of the air in the wind-chest 43 will, through the connecting conduit 42, effect the collapse of pneumatic 39, and the collapse of pneumatic 39 will, through the link 40, draw the upper end of the push-rod 26 25 to the left (as shown in Fig. 1), out of operative engagement with the longer horizontal arm of the bell-crank-lever 27, and thus render the "piano" pedal 17 ineffective to shift the piano action 11.

30 In Fig. 4 is shown another form of construction for rendering the push-rod 26 ineffective to cause movement of the bell-crank-lever 27^a when the piano is played automatically. In this form of my invention, movement of the bell-crank-lever 27^a is prevented, when the piano is played automatically, by the interposition of the slidable block 44 into the path of the extension 45 of the bell-crank-lever 27^a. This block 44 is 35 mounted on a rod 46 which is actuated by the pneumatic 39^a, which may be connected with the wind-chest 43 in the same way as is the pneumatic 39, previously described. A suitable guide 47 may be provided for 40 the rod 46. The bell-crank-lever 27^a is operatively associated with the slidable key-frame 30, just as is the bell-crank-lever 27 in the construction previously described. With 45 this construction, rarefaction of the air in the windchest 43 will, through the connecting conduit 42, effect the collapse of pneumatic 39^a, and the collapse of pneumatic 39^a will, by means of the slidable rod 46, interpose the block 44 in the path of the extension 50 45 of the bell-crank-lever 27^a, and thus render the "piano" pedal 17 ineffective to shift the slidable key-frame 30 and the piano action carried thereby.

In Figs. 5 and 6, I have shown another 60 form of my invention, in which means are

provided for preventing injury to the stickers 34 by the operation of the "piano" pedal 17. In this form of my invention, the stickers 34 are guided near their upper ends by means of a movable guide-bar 48, which is 70 provided with a construction whereby it will be shifted along with the key-frame 30 when the latter is shifted by means of the "piano" pedal 17, so that the stickers 34 will at all times be in alignment with the keys 25 75 mounted on the key-frame 30, the construction being such, however, that the key-frame 30 may be withdrawn and inserted without interference with or from the guide-bar 48. The guide-bar 48 may be mounted, for lateral movement, by means of a pair of swinging links 49, pivotally connected at 50 with the guide-bar 48 and pivotally connected at 51 with any suitable fixed part of the piano 80 construction. In order that the guide-bar 48 will be shifted along with the key-frame 30 when the latter is shifted, a pair of cheek-pieces 52 are provided, one secured to each end of the guide-bar 48, these cheek-pieces between them receiving the rear bar 53 of the key-frame 30. The construction is such that when the key-frame 30 is pushed back into position, it will engage snugly between the cheek-pieces 52. These cheek-pieces 52 flare 85 outwardly, as shown in Fig. 6, to facilitate 90 the reception of the rear bar 53 of the key-frame.

By referring to Fig. 6, it will be seen that when the "piano" pedal 17 is operated to shift the key-frame 30, (including the rear 100 bar 53), the guide-bar 48 will be shifted also and thus maintain the stickers 34 in alignment with the keys 25. This prevents any possibility of a sticker being jammed sideways by sliding movement of the key-frame 105 during automatic playing of the piano.

In Fig. 7 is shown another form of my invention, in which the stickers 34 are guided near their upper ends by means of a movable guide-bar 54, slidably mounted in a channel 55 in the key-bed 10. This guide-bar 54 is provided with cheek-pieces similar in shape and function to the cheek-pieces 52, between which the rear bar 53 of the key-frame 30 is received.

115 In this construction also, when the "piano" pedal 17 is operated to shift the key-frame 30, (including the rear bar 53), the guide-bar 54 will also be shifted, and thus maintain the stickers 34 in alignment with 120 the keys 25.

Having thus described my invention, what I claim as new and desire to secure by Letters Patent of the United States is:

1. The combination with an automatic 125 piano having a slidable action, an automatic action for cooperation with said slidable action, and means for causing sliding movement of said slidable action, of means for rendering said means for causing sliding 130

movement ineffective when the piano is played automatically.

2. The combination with a manually and automatically operable piano having a slideable action, an automatic action for cooperation with said slideable action, and manually operable means for causing sliding movement of said slideable action, of means for automatically rendering said means for causing sliding movement ineffective when the piano is played automatically.

3. A manually and automatically operable piano having two alternatively usable pianissimo devices, the first of said devices being usable when the piano is played manually, the second of said devices being usable when the piano is played automatically, and means for preventing the use of the first of said devices when the piano is played automatically.

4. A manually and automatically operable piano having two alternatively usable pianissimo devices, the first of said devices being usable when the piano is played manually, the second of said devices being usable when the piano is played automatically, and means for preventing the use of the first of said devices when the piano is played automatically; said piano comprising a slideable action having hammers operable either automatically or manually, and said first of said devices causing sliding movement of said slideable action.

5. A manually and automatically operable piano having two alternatively usable pianissimo devices, the first of said devices being usable when the piano is played manually, the second of said devices being usable when the piano is played automatically, and means for preventing the use of the first of said devices when the piano is played automatically; said piano comprising a slideable action, and an automatic action for cooperation with said slideable action, and said first of said devices comprising means for causing sliding movement of said slideable action.

6. A manually and automatically operable piano having two alternatively usable pianissimo devices, the first of said devices being usable when the piano is played manually, the second of said devices being usable when the piano is played automatically; said piano comprising a slideable action, and an automatic action for cooperation with said slideable action, said first of said devices comprising means for causing sliding movement of said slideable action, and means for automatically rendering said means for causing sliding movement ineffective when the piano is played automatically.

7. The combination with a manually and automatically operable piano having a slideable action, an automatic action comprising

reciprocable stickers for lifting the keys of said slideable action, and manually operable means for causing sliding movement of said slideable action, of means for preventing injury to said stickers during the sliding movement of said slideable action.

70

8. The combination with a manually and automatically operable piano having a slideable action, an automatic action comprising reciprocable stickers for lifting the keys of said slideable action, and manually operable means for causing sliding movement of said slideable action, of means for preventing injury to said stickers by the operation of said manually operable means.

75

9. The combination with a manually and automatically operable piano having a slideable action, an automatic action comprising reciprocable stickers for lifting the keys of said slideable action, and manually operable means for causing sliding movement of said slideable action, of means for preventing injury to said stickers by the operation of said manually operable means, said manually operable means comprising a foot-pedal.

80

10. The combination with a manually and automatically operable piano having a slideable action, an automatic action comprising reciprocable stickers for lifting the keys of said slideable action, and manually operable means for causing sliding movement of said slideable action, said manually operable means comprising a foot-pedal; of means for preventing injury to said stickers by the operation of said foot-pedal.

90

11. The combination with a manually and automatically operable piano comprising a slideable action, of means for causing sliding movement of said action, and means for automatically rendering said means for causing sliding movement ineffective when the piano is played automatically, comprising a pneumatic controlled by the playing pressure.

95

12. The combination with a manually and automatically operable piano comprising a slideable action, of means for causing sliding movement of said action, and means for automatically rendering said means for causing sliding movement ineffective when the piano is played automatically, comprising a pneumatic controlled by the playing pressure, the first said means comprising a push-rod and a bell-crank operated by said push-rod, and the second said means comprising means for rendering said push-rod ineffective to operate said bell-crank.

105

In witness whereof, I have hereunto subscribed my name.
